UNITED STATES PATENT OFFICE.

ALFRED JOHN CRANTZ, OF DENVER, COLORADO.

LADY'S HATBOX.

Application filed July 22, 1922. Serial No. 576,674.

To all whom it may concern:

Be it known that I, ALFRED JOHN CRANTZ, a citizen of the United States, residing at the city and county of Denver and State of Colorado, have invented certain new and useful Improvements in Ladies' Hatboxes; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to hat boxes, and has special reference to a box adapted to contain a lady's hat while traveling.

Ladies' hats, as a general rule, are difficult to transport owing to their size and delicate construction, and in order to make it reasonably safe to have them shipped by auto or train, it is necessary to provide a box for their reception. Such boxes should be made of substantial yet rigid construction, and should also be of neat and pleasing appearance.

It is the object of this invention to produce a box that shall be adapted to contain a lady's hat, furs, gloves and toilet articles, 30 and which shall be so designed and constructed that it will be convenient to open and shut, and which will protect the hat from injury while it is enclosed therein, and which will also be adapted to stand on the 35 floor or to be hung on suitable supporting means on the wall.

In order to more clearly describe my invention, I shall have reference to the accompanying drawing, in which

40 Fig. 1 is a perspective view of my box in closed position;

Fig. 2 is a perspective view thereof in open position;

45 Fig. 3 is a section taken on line 3—3, Fig. 1; and

Fig. 4 is a detail showing how the mirror is held in place.

The same reference numerals will be used to designate the same parts throughout the 50 several views.

My improved box consists of a bottom member 1 which is preferably rectangular in shape and is about twenty-four (24) inches long and eighteen (18) inches wide. To 55 the longer sides of member 1 I secure sides 2 and 3, and to the shorter sides I secure

the end members 4 and 5, the former of which will be referred to as the upper and the latter as the lower end member. The bottom, sides and end members are formed 60 of thin, veneered board, cardboard, fibre or any other similar material, and are secured together along their edges by means of glue or cement, or other approved means, so as to form a box open on one side. The edges of 65 the box are bound by strips 6 of leather, fibre, or metal, which are sewed or riveted along the edges as indicated by numeral 7. The corners are protected by means of trunk corners 8 of suitable material. The upper end 70 4 is provided with a trunk handle 9 by means of which the box can be carried. Secured to each side is a cover member 10 and 11, which are connected to the sides by flexible means which permit them to swing relative to the 75 sides whereby they may be closed as shown in Fig. 1, or opened as shown in Fig. 2. Near the upper end of each of the cover members I provide springs 12 which are tensioned to hold the doors open as shown in Fig. 2, but 80 which will permit them to close in the manner shown in Fig. 1. Near the lower end of the box I secure a wide, thin strip of cardboard or other material 13 which has its ends 14 secured to the sides by means of 85 rivets or cement, and whose lower edge is secured to the outer curved edge of the lower end member 5. The strip 13 cooperates with the lower end member 5, sides 2 and 3, and bottom 1 to form a box-like compartment 90 which is adapted to receive and contain furs or other pieces of ladies' apparel. In the centre of the bottom compartment just described I place a box 15 which has a cover 16, shown open in Fig. 2 and closed in Fig. 95 3. Box 15 may be used for the reception of toilet articles such as powder, cold cream, tooth brushes, tooth paste, etc. Secured to the bottom member 1, near the top thereof, is a cylindrical member 17 which is made of 100 such material that a hatpin can be readily passed therethrough. The hat, shown dotted, is placed with its crown over the member 17, and a hatpin (not shown) is passed through the hat and the support, and serves 105 to hold the hat in place.

The front end of the supporting member 17 is provided with an inwardly projecting flange 18 which serves to hold removably a mirror 19. A curved strip 20, similar to the curved member 13, is secured to the curved edge of the upper end 4, and serves as a 110

means against which the top edges of the covers fit. A staple 21 is secured to the bent member 13 and passes through the openings 22 in covers 10 and 11. A similar staple 23 is secured to cover 10 and passes through opening 24 when the covers are in closed position.

To protect the upper end of the covers from moisture and dust, I provide a cover member consisting of a downwardly projecting part 25 which is secured to the front curved edge of the hinged member 26. A strap 27 is secured to the member 25 and when the box is closed the strap 27 is inserted through the staples 21 and 23 and serves to prevent the opening of the covers. A hole 28 is provided in the end of the strap 27 and serves to receive the bail of a padlock whereby the strap is locked in place. On each side I secure a bracket 29 which serves as a support for gloves and similar articles. The bottom may be provided with holes 30 through which hooks or screws may be inserted when the box is secured to the wall. The mirror 19 may be removed from the holder 18 and used as a hand mirror. The interior of the box may be lined with suitable material which has not been shown, as the same is for ornamental purposes only. From the above it will appear that I have devised a hat box that is well adapted to receive a lady's hat and to protect the same from injury. The box described is also so designed that it can be hung on the wall of a dressing room and used as a cabinet containing toilet and other articles. As it is provided with a mirror, it is, when hung on the wall, adapted for use as a dresser. When traveling the box can be carried as hand luggage, or can be checked as baggage, and in either case the hat will be safe from damage.

Having now described my invention, what I claim as new is—

1. A hat box having a large compartment adapted to receive a hat, a projection in said compartment to the outside of which said hat may be attached, and a separate covered compartment within said large compartment adapted to receive toilet articles. 45

2. A hat box having substantially rectangular sides and bottom, and ends having the upper sides thereof curved, a cover member secured to each side and adapted to overlap each other to form a closure, and a flap hinged to the end of the box adapted to cover 50 the upper ends of said cover sections. 55

3. A hat box, comprising a rectangular body portion formed from a bottom piece, two sides and two end members, the end members having their top edges upwardly curved, a cover member secured to each side member and adapted to form a closure, said cover members being of such a size that they will overlap, a curved member extending from one side to the other near the bottom 60 thereof, whereby a container is formed for the reception of minor loose articles, and means to hold the closure members from 65 opening. 65

4. A hat box, comprising a rectangular body portion formed from a bottom piece, two sides and two end members, the end members having their top edges upwardly curved, a cover member secured to each side member and adapted to form a closure, said 70 cover members being of such a size that they will overlap, a curved member extending from one side to the other near the bottom thereof, whereby a container is formed for the reception of minor loose articles, and 75 means to hold the closure members from opening, said means comprising a pair of staples and a flexible member adapted to be 80 inserted therethrough. 80

In testimony whereof I affix my signature.

ALFRED JOHN CRANTZ.
